UNITED STATES PATENT OFFICE.

BERTHOLD L. BLATT, OF FREEDOM, PENNSYLVANIA, ASSIGNOR OF ONE-THIRD TO JAMES H. JOHNSTON, OF WAMPUM, PENNSYLVANIA, AND ONE-THIRD TO WILLIS C. JACK, OF FREEDOM, PENNSYLVANIA.

DETERGENT COMPOUND.

No Drawing.

Application filed January 3, 1925. Serial No. 436.

To all whom it may concern:

Be it known that BERTHOLD L. BLATT, a citizen of the United States, residing at Freedom, in the county of Beaver and State of Pennsylvania, has invented certain new and useful Improvements in a Detergent Compound, of which the following is a specification.

My invention relates to a detergent compound or mixture for cleaning and renovating painted or varnished surfaces.

An object of my invention is to produce a detergent which will renovate as well as clean painted and varnished surfaces and which will not fade, scratch or marr such surfaces.

A detergent which will accomplish such objects, as above stated, is composed of a phosphate, a borate and a glue. Preferably, though not necessarily, I use sodium phosphate as the phosphate, borax as the borate, and powdered animal glue as the glue.

The proportions of the above ingredients which I have found to make a very satisfactory detergent or cleaner are as follows: sodium phosphate, 30%; borax, 68%; powdered glue, 2%.

About one ounce of this mixture is dissolved in two quarts of either hot or cold water to form an aqueous solution. I use borax, which is in itself a cleaner, in my compound, to remove the heavy dirt and grease from the surface operated upon. Sodium phosphate is used as it is an excellent paint cleaner, but is too harsh in its individual action to be applied to varnished or other highly lustrous surfaces. However, by combining it with borax, I modify its action and obtain a satisfactory cleaning product. The addition of glue to the borax and sodium phosphate gives me a compound which cleans as well as acts as a polish and filler for lustrous and glossy surfaces.

An aqueous solution of the above ingredients is applied to the surface to be worked on by means of a sponge, cloth, or brush. A single application generally suffices to remove the dirt and grease therefrom and to restore the original luster to the surface.

After the surfaces have been cleaned they are dried with a cloth to remove the excess moisture.

My detergent is adaptable for use on polished, varnished or painted surfaces as well as on dull surfaces. It may also be utilized to clean window shades and silver. The mildness of the solution makes it very easy on the hands of the operator using it and its simple method of application a boon to housewives.

Having thus fully described my invention what I claim as new and desire to secure by Letters Patent is:

1. A composition of matter for cleaning and renovating painted or varnished surfaces, consisting of sodium phosphate, sodium borate, and glue.

2. A composition of matter for cleaning and renovating painted or varnished surfaces, consisting of sodium phosphate 30%, sodium borate 68%, and glue 2%.

3. A composition of matter for cleaning and renovating painted or varnished surfaces, consisting of an aqueous solution of sodium phosphate, sodium borate and glue.

4. A composition of matter for cleaning and renovating painted or varnished surfaces, consisting of three-tenths of an ounce of sodium phosphate, sixty-eight one-hundredths of an ounce of sodium borate, and two one-hundredths of an ounce of powdered glue, dissolved in two quarts of water.

In testimony whereof I affix my signature.

BERTHOLD L. BLATT.
